UNITED STATES PATENT OFFICE.

LILLY L. HULL, OF FOREST HILL, NEW JERSEY.

SAFETY-BELT.

No. 895,021.

Specification of Letters Patent.

Patented Aug. 4, 1903.

Application filed May 9, 1907. Serial No. 372,770.

To all whom it may concern:

Be it known that I, LILLY L. HULL, a citizen of the United States, residing at Forest Hill, Essex county, New Jersey, have invented certain new and useful Improvements in Safety-Belts, of which the following is a full, clear, and exact description.

My invention relates to improvements in women's wearing apparel, and pertains particularly to waist-belts for the purpose of supporting sanitary napkins.

The object of the invention is to provide a belt of pliable material, adapted to be worn about the waist, which is capable of a nice adjustment, and which will afford ease and comfort to the wearer.

In the drawings Figure 1 is a perspective view; Fig. 2 is a front elevation showing the sanitary bandage in outline.

20. 1 is a belt of any pliable material, for instance cloth, adapted to encircle the waist of the wearer, and which is of such shape as to readily conform to the contour of the figure. The front and back portions of the belt 1 are 25 provided with two depending pad projections 2—2. Depending from these projections 2—2 are elastics 3—3.

4—4 are pin tabs secured to the lower ends of the elastics 3—3.

30. 5—5 are elastic strips inserted in the belt on opposite sides thereof.

The article may be divided in front and provided with buttons and button-holes.

It will be readily seen that the article is of such construction that it will automatically 35 adjust itself to the numerous changes of position and movements of the wearer, and thus afford the user great ease and comfort.

Heretofore it has been customary to support the sanitary napkin at substantially one point and relatively rigidly. Old methods of attachment caused the upper parts of the napkin to bunch or wrinkle, thus causing the user much annoyance and great discomfort, and producing an unsightly bulging of the 45 outer garments. By my improvement, the napkin, when fastened to the belt, lies perfectly flat, thus avoiding the discomfort above referred to, and permitting the outer garments to fit perfectly smooth over the 50 figure.

What I claim is—

A safety belt comprising two rear pads connected together by a contracted portion, two front pads detachably connected together 55 by a contracted portion and connected to the rear pads by narrow elastic strips, and pin tabs suspended from said pads by elastic connections.

LILLY L. HULL.
